R. H. OLIVER.

BRAKE BEAM.

APPLICATION FILED MAR. 31, 1921.

1,418,391.

Patented June 6, 1922.

Inventor,

R. H. Oliver

By - C. J. Fetherton Haug.

Atty.

UNITED STATES PATENT OFFICE.

RICHARD HUGHES OLIVER, OF BRIDGEBURG, ONTARIO, CANADA.

BRAKE BEAM.

1,418,391.

Specification of Letters Patent. Patented June 6, 1922.

Application filed March 31, 1921. Serial No. 457,173.

To all whom it may concern:

Be it known that I, RICHARD HUGHES OLIVER, a subject of the King of Great Britain, and resident of the town of Bridgeburg, 5 in the county of Welland, in the Province of Ontario, in the Dominion of Canada, have invented certain new and useful Improvements in Brake Beams, of which the following is a specification.

10 The invention relates to improvements in brake beams as described in the present specification and shown in the accompanying drawings that form a part of the same.

15 The invention consists essentially of the novel features of construction whereby a brake beam is provided with a reversible strut.

20 The objects of the invention are to provide a form of strut which may be used to equal advantage on either side of the car, thus eliminating the necessity of providing left and right hand struts, and generally to provide a beam which will be inexpensive to manufacture, simple to adjust, efficient in 25 operation and durable.

In the drawings Figure 1 is a side elevation of a portion of a brake beam showing the strut in position.

Figure 2 is a longitudinal sectional view 30 taken on the line A—A of Figure 1.

Figure 3 is a cross sectional view taken on the line B—B of Figure 1.

Figure 4 is an end view of Figure 1.

Figure 5 is a cross sectional view taken on 35 the line C—C of Figure 2.

Like numerals of reference indicate corresponding parts in the various figures.

Referring to the drawings 1 is the brake beam to which is secured the brace 2 as cus- 40 tomary in brake beam construction.

3 is a casting substantially cross shape in cross section and having an enlarged end portion 4 adapted to be secured to the beam 1 by suitable fasteners 5, the other end of 45 said casting being in the form of a preferably circular disc 6 having openings therethrough for the reception of locking bolts 7 and being provided with an inwardly projecting key slot 8.

50 9 is a casting slotted at one end as at 10 to receive the brace 2 and being provided with a transversely arranged opening adapted to accommodate a pin 11 for locking said casting on said brace, said casting at its 55 inner end being formed with an integral disc 12 similar to the disc 6 and located di-

rectly opposite said disc 6 and having a key slot 13 therein.

14 is the strut, each end of which is provided with a plate 15 of equal dimensions 60 with the discs 6 and 12 being adapted to be rigidly secured therebetween by means of bolts 7, said strut being provided with a longitudinal slot 16 therethrough adapted to receive the brake lever 17 which is pivotally 65 secured by means of a pin 18, said slot being cut at the proper angle to permit of said brake lever extending diagonally in relation to the brake beam 1 and meeting the brake lever from the opposite side of the car. 70

The strut is preferably provided at each end with a projection or key 20 adapted to be inserted in the slots 8 and 13 respectively.

21 is a boss preferably formed integral with the casting 9 and having a suitable 75 opening 22 therethrough for the reception of a chain or other member (not shown in the drawings) for securing said casting to the car frame or other support, for the purpose of supporting said casting upon the removal 80 of the strut.

In the use of this invention it will be apparent that the strut 14 may be used on either side of the car with equal facility by simply securing same between the castings 3 and 9 85 with the slot 16 extending in the position necessary to permit of the proper positioning of the back lever 17.

What I claim is:—

1. In a brake beam, in combination, a 90 beam, a brace, a head permanently secured to said beam, a head comprising a casting slotted at one end to receive said brace and adapted to be locked thereto by means of a pin extending across said slot, said heads 95 being enlarged to form flat faces oppositely disposed in relation to one another, said faces being provided with bolt holes therethrough, and a strut having flat end surfaces adapted for engagement with said faces. 100

2. In a brake beam, in combination, a beam, a brace, a head permanently secured to said beam, a head comprising a casting slotted to receive said brace, a pin extending transversely through said casting and across 105 said slot for locking said head to said brace, each of said heads being provided with an enlarged inner end presenting a flat outer face, and a strut provided with enlarged end portions presenting flat outer surfaces adapted 110 for engagement with said faces, said enlarged portions being provided with open-

ings for the reception of fastening members. 3. In a brake beam, in combination, a beam, a brace, a head permanently secured to said beam, a head comprising a casting slotted to receive said brace, a pin extending transversely through said casting and across said slot for locking said head to said brace, each of said heads being provided with an enlarged inner end presenting a flat outer face, a strut provided with enlarged end portions presenting flat outer surfaces adapted for engagement with said faces, said enlarged portions being provided with

openings for the reception of fastening members, said strut being provided with projections from the ends thereof adapted to enter slots in the enlarged portions of said heads, and a pierced lug integral with the head carried by said brace. 15

Signed at the city of Toronto, this 18th day of March, 1921.

RICHARD HUGHES OLIVER.
